CIRCUIT INTERRUPTER

John H. Shuler, Lexington, Ohio, assignor to Westinghouse Electric & Manufacturing Company, East Pittsburgh, Pa., a corporation of Pennsylvania

Application January 23, 1934, Serial No. 707,908

14 Claims. (Cl. 200—122)

My invention relates generally to electro-responsive devices for actuating electrical apparatus, and relates particularly to trip devices for circuit breakers of the type used in controlling 5 distribution feeder and moderate power industrial circuits.

Circuit breakers of this type are usually subjected to very severe and very exacting operating requirements. The available power in the 10 supply circuits is frequently extremely large, as compared with the normal rating of the device. This results in very large magnitude short-circuit currents which must be interrupted in very short periods of time in order to prevent damage 15 to the protected equipment. And despite this necessity for rapid operation upon the occurrence of short-circuit conditions, the breakers must remain closed for a considerable time following the occurrence of moderate overloads, in order 20 to prevent needless and annoying discontinuities of service.

The securing of this desired selective operation is entirely a function of the circuit breaker trip device, and heretofore various complicated structures have been in general use. Some of these 25 have utilized a combined thermally-responsive and magnetically-responsive trip element. Others have combined thermally responsive and magnetically-responsive devices simultaneously 30 actuatable to prevent injury to the current-carrying portions thereof upon the occurrence of overloads or short-circuit conditions. All of the previously known devices have been expensive to manufacture, most of them including a considerable 35 number of moving parts, any one of which might get out of adjustment and thereby destroy the calibration of the apparatus, and none has been entirely satisfactory.

It is, therefore, an object of my invention to 40 provide an improved electro-responsive device for use with electrical apparatus that shall be more economical to manufacture, and more accurate and reliable in operation than the previously known devices of this type.

Another object of my invention is to provide 45 an improved current-carrying thermally-responsive device that shall possess sufficient thermal capacity to withstand heavy overload and short-circuit currents, and which shall at the same time 50 be operable to actuate the associated apparatus upon the flow therethrough of predetermined low magnitude currents.

A further object of my invention is to provide 55 an improved circuit breaker trip device that shall accurately distinguish between overloads and short-circuit conditions, and that shall not readily lose its calibration.

A still further object of my invention is to provide 60 an improved, unitary, circuit breaker trip device that shall include a bimetallic element,

a heater, and means for controlling the rate of heat transfer therebetween.

An ancillary object of my invention is to provide an improved electro-responsive device, according to the above objects of my invention, 5 that shall be readily removable as a unit from the associated apparatus to permit the substitution therefor of other similar devices in order to alter the rating of the associated apparatus.

Since the principal field for immediate application of my invention is in connection with circuit breakers for moderate power installations, I shall hereinafter describe an embodiment of my invention as applied to such devices, without, however, in any way intending to restrict the 15 scope of my invention, except as indicated in the appended claims.

Referring to the drawings:

Figure 1 is a plan view of a two-pole, double break circuit breaker embodying the principal 20 elements of my invention. The breaker is shown in the normal open circuit position, and a considerable portion of the cover has been cut away in order to more fully illustrate the structural features involved;

Fig. 2 is a plan view similar to Fig. 1 showing 25 the circuit breaker in the closed circuit position;

Fig. 3 is a plan view similar to Figs. 1 and 2 showing the circuit breaker in the tripped position;

Fig. 4 is an enlarged detail view of the removable trip device used in the circuit breaker shown in Figs. 1, 2, and 3;

Fig. 5 is a perspective view of the trip device shown in Fig. 4;

Fig. 6 is a detail view, partly in section, of the moving contacts and the support member therefor;

Fig. 7 is an exploded perspective view of the trip device illustrated in Figs. 4 and 5;

Fig. 8 is an enlarged perspective view, partly 40 in section, showing the stationary contact assemblies and a portion of the breaker closure;

Fig. 9 is an enlarged perspective view of the frame of the circuit breaker operating mechanism; and

Fig. 10 is an enlarged perspective view of the cradle used for supporting the movable contacts.

This preferred embodiment of my invention comprises generally a base 1 of molded insulating material upon which the various structural features of the device are mounted, a pair of stationary contact assemblies 3 and 5, four terminals 7, 8, 9, and 10, a pair of moving contacts 11 and 13 for cooperating with the stationary 50 contact assemblies to open and close the circuit, an operating mechanism 15 for moving the contacts to the open and closed circuit positions, and a trip device 17 for causing the operating mechanism 15 to open the circuit upon the oc- 55 60

currence of predetermined conditions. Four up-standing side portions 19 are molded integral with the base 1 and serve to provide the sides of the circuit breaker closure. A cover 21 also of molded insulating material is provided for cooperating with the side portions 19 to substantially completely enclose the operating portions of the breaker.

Each of the stationary contact assemblages 3 and 5 includes a flexible contact portion 23 and 10 a flexible contact portion 31 (Fig. 8) for engaging the cooperating moving contact. The contact portions 23 are mounted upon an upstanding member 25, molded integral with the base 1, by suitable screws 27. These screws 27 also serve to 15 position the two terminals 7 and 8, and to electrically connect those terminals with the contact portions 23. Each of the terminals 7 and 8 has a threaded opening therein (not shown) for engaging one of the screws 29 which are used to 20 connect the line conductors to the breaker.

The second pair of flexible contact portions 31 is positioned closely adjacent the base 1 of the breaker, and each of the flexible contact portions 31 terminates in a flat conducting strip 33 fastened to the base 1 by a screw 34. The upper conducting strip 33 is electrically connected by suitable means (not shown) to the terminal 10. The lower conducting strip 33 is electrically connected to a cylindrical member 35 molded integral 30 with one of the side portions 19 (Fig. 8) by means of a screw 37. This cylindrical member 35 is used for electrically connecting the trip device 17 in series with one of the poles of the breaker and is provided with a threaded opening 41 therein 35 for engaging one of the support screws 43 for the trip device.

A second cylindrical member 45 of conducting material, likewise molded in the side portions 19 of the breaker closure, is provided for engaging 40 the other terminal of the trip device 17. The interior of this cylindrical conducting member 45 is likewise threaded for receiving the other support screw 43. The lower end of the cylindrical conducting member 45 is connected to the terminal 9 of the breaker by means of a suitable 45 conducting strip 47 which engages the screw 49 holding the terminal 9 in position on the base of the circuit breaker.

The electrical circuit through each of the poles 50 of the breaker is comparatively direct: Beginning with terminal 1 the current flows successively through the flexible contact portion 23 of the stationary contact assemblage 3 thence through the cooperating movable contact 11 to the other 55 flexible contact portion 31 of stationary contact assemblage 3, through the conducting strip 33 associated with the contact portion 31, and suitable conducting means (not illustrated) to the terminal 10. For the other pole, the current flows 60 successively through the terminal 8, the upper flexible contact portion 23 of the stationary contact assemblage 5, the moving contact 13, the lower flexible contact portion 31 and the associated strip 33, the cylindrical conducting member 65 35, the terminal 51 of the trip device 17, and thence through the trip device 17, the cylindrical conducting member 45, the strip 47 and the screw 49 to the other terminal 9 of the breaker.

The moving contacts 11 and 13, as is shown 70 particularly in Fig. 6, are mounted upon a support member 53 which is adapted to pivotally engage the cradle member 55 of the operating mechanism 15 at the point 56. Each of the moving contacts comprises a pair of cylindrical members 75 57 and 59 of conducting material. Each of the

members 57 is provided with a threaded portion 61 for engaging a threaded opening 63 in each of the members 59. An insulating plate 65 is interposed between each of the cylindrical members and the support member 53, and these insulating plates 65 in combination with an insulating washer 67 serve to insulate each of the two moving contacts from each other and from the support member. 5

The operating mechanism includes a frame 69 10 (see Fig. 9) which is rigidly affixed to the base 1 of the circuit breaker by means of suitable screws 70 which engage the threaded openings 71 therein, a bifurcated operating member 73 adapted to be pivotally supported upon two portions 75 which 15 project outwardly from the frame 69, an over-center spring 77 for operatively connecting the support member 53 for the moving contacts with the operating member 73, and the movable cradle 55 (Fig. 10) which is provided with a pair of 20 notched portions 79 for engaging and pivotally supporting the support member 53 for the moving contacts. The cradle 55 is pivotally supported upon the frame 69 by means of a pin 81 and is provided with a roller 83 for engaging the projecting latch 85 which forms a part of the trip device 17. The operating member 73 is provided with a handle portion 87 disposed without the circuit breaker closure, in order to permit manual operation of the mechanism. 30

The trip device is shown particularly in Figs. 4, 5, and 7, and includes a frame 91 of conducting material which serves to support the several elements of the device and which has the terminal 51 formed integral therewith. A pair of bimetallic strips 93 having a length several times their width are fastened to the frame 91 by means of suitable rivets 95. The lower end of the left-hand bimetallic strip 93 (see Fig. 7) is electrically connected to the frame 91. The lower end of 40 the other bimetallic strip 93, however, is insulated from the frame 91 by means of a piece of mica 97 interposed therebetween. The other terminal 99 of the trip device is electrically connected to the lower end of the right-hand bimetallic member 93. The upper ends of the two bimetallic strips are mechanically connected by means of a pair of plates 101 of insulating material, a retaining plate 103, a latch plate 105, and two rivets 107 which engage suitable holes 50 in the several members. The latch plate 105 is insulated from the two bimetallic strips 93 by one of the insulating plates 101, and the spacing of the holes is such that two ends of the bimetallic strips 93 are insulated from each other. 55

The electrical circuit through the trip device 17 is completed by means of a looped heater 109, one end of which is electrically connected to each of the bimetallic strips 93 by means of a rivet 111 adapted to extend through suitable openings 60 disposed therein. As shown particularly in Figs. 4 and 7, the heater 109 comprises a plurality of substantially flat looped portions which are disposed in a plane spaced some distance from the plane of the bimetallic strips themselves. It will 65 also be noted that an insulating plate 113, preferably of mica, is interposed between the flat portion of the heater and the adjacent surfaces of the bimetallic strips 93. This insulating member 113 in combination with the spacing of the heater 70 serves to reduce the rate of heat transfer between the heater and the thermally-responsive bimetallic strips in order to increase the time delay of the trip device when moderate overload currents flow therethrough. 75

The latch plate 105 is provided with an outwardly projecting latch portion 85 for engaging the roller 83 forming the part of cradle 55, as is shown particularly in Figs. 2 and 4. The bimetallic strips 93 are so positioned that upon heating they both tend to move the latch plate 105 in a direction away from the operating mechanism 15, and when this movement progresses a sufficient distance to cause the latch 85 to release the roller 83, the operating mechanism automatically opens the breaker.

From the foregoing description, it will be seen that the trip device 17 comprises a pair of bimetallic elements 93, each of which has a current-carrying portion, and a heater 109, which is entirely supported upon the bimetallic elements, and which is in series with and connects the two current-carrying portions thereof. The electrical resistance and the thermal capacity of the bimetallic elements 93 are so proportioned that the flow of large magnitude currents through the current-carrying portions of the bimetallic strips produces sufficient internal heating to cause the actuation of the trip device after a very short interval of time. The thermal capacities and the resistances of the current-carrying paths are so proportioned, however, that the continued flow of moderate over-load currents through the bimetallic elements themselves would be incapable of causing the actuation of the trip device. This inability results from the high thermal capacity of the bimetallic elements, which is necessary in order to prevent any injury to the calibration of the device following the flow therethrough of large magnitude currents.

The inability of the trip device 17 to function when low magnitude currents flow therethrough necessitates the provision of the separate heater 109. The resistance of this heater and its thermal capacity are such that the continued flow of moderate over-load currents therethrough will produce sufficient heating to cause the operation of the trip device in substantially the same manner as that resulting from the flow of large over-load currents through the bimetallic elements themselves. I have found that the time delay may be very readily and very accurately controlled by adjusting the spacing between the heater 109 and the bimetallic strips 93 themselves and also by inserting a piece of insulating material, such as the mica plate 113 in that space. The combination of these structural features results in a trip device which is almost instantaneously operable to cause opening of the circuit upon the occurrence of a short-circuit or a very heavy over-load condition, and which at the same time will not cause the opening of the controlled circuit upon the occurrence of a moderate over-load condition, until that condition has persisted for a considerable period of time. Moreover, this improved arrangement permits the utilization of current-carrying bimetallic elements, having sufficient thermal capacity to withstand, without injury, the flow therethrough of heavy over-load current, in trip devices operable to cause opening of the associated breaker upon the occurrence of moderate overloads.

The circuit breaker is shown in the open circuit position in Fig. 1. To close the contacts manually the handle 87 of the operating member 13 is moved to the right. This movement brings the line of action of the over-center spring 77 across the pivot point 56 of the support member 53 for the moving contacts 11 and 13, and causes those contacts to move to the closed circuit position

with a snap action. Both of the poles of the breaker are closed at substantially the same instant. The closed circuit position is shown in Fig. 2, and it will be noted that the reaction forces of the over-center spring 77 which are transmitted through the contact support member 53 tend to bias the cradle 55 in a counter-clockwise direction about the cradle pivot pin 81. This biasing force is opposed by the latch portion 85 of the trip device 17.

To open the contacts manually, the operating handle 87 is moved from the position shown in Fig. 2 to the position shown in Fig. 1. The line of action of the over-center spring 77 is brought to the left of the pivot point 56 of the support member 53 for the moving contacts, and the opening operation takes place with a snap action in substantially the same manner as the closing operation.

When the circuit breaker is in the closed circuit position, and an over-load of sufficient magnitude and duration to cause actuation of the trip device 17 occurs, the bimetallic strips 93 move so as to cause the latch 85 to disengage the cradle roller 83. The cradle 55 is then free to move in a counter-clockwise direction, and in so moving brings the pivot point 56 of the support member 53 for the moving contacts to the right of the line of action of the operating spring 77. The operating spring then moves the moving contacts to the position shown in Fig. 3. In this position, the projecting portion 115 of the cradle, which supports the roller 83, engages the member 117 which is molded in the base 1, thereby defining the limits of motion of the cradle. The positioning of the pivot points of the other elements of the operating mechanism 15 is such that the handle 87 moves to the central position, thereby indicating that the circuit has been opened due to the operation of the trip device 17.

In order to restore the various elements of the operating mechanism 15 to an operative condition following the actuation of the trip device 17, it is merely necessary to move the operating handle 87 to the normal open circuit position shown in Fig. 1. This movement of the operating handle is transmitted to the cradle through the engagement of the side portions 119 of the bifurcated operating member 13 with the lugs 121 forming a part of the cradle 55, and causes the cradle to rotate in a clockwise direction to a position where the roller 83 re-engages the latch 85 forming a part of the trip device. The breaker may then be manually moved to the closed circuit position in exactly the same manner as described above.

As has been pointed out in a previous paragraph, the trip device is entirely supported from the frame member 91, which also serves as one of the terminals of the device. The other terminal 99, while it is insulated from the frame member, is rigidly affixed thereto. Thus the removal of the two screws 43, which serve to connect the trip device 17 in the electrical circuit of the breaker, also permits the trip device 17 to be entirely removed as a unit from the breaker closure. This arrangement is of great value in permitting the rating of the breaker to be changed through the substitution of a similarly proportioned device having a different current rating. Moreover, since the single heater 109 for both of the bimetallic elements 93 is mounted thereon, the removal of the trip device also serves to remove the heater.

I have shown a trip device in the circuit of only one of the poles of the breaker. It is possible, however, and within the province of my invention, that a trip device may be used in both poles with equally satisfactory results.

From the foregoing it will be seen that I have disclosed a new, improved, electro-responsive device which is particularly suitable for use as a circuit breaker trip device. My improved electro-responsive device is simple in design and may be economically manufactured. It is capable of causing the actuation of apparatus used therewith almost immediately following the occurrence of heavy over-load or short-circuit conditions, without any change in the calibration or any injury to the current-carrying parts thereof, and at the same time, my improved device is capable of causing the actuation of the associated apparatus upon the persistence of 20 moderate over-loads in the connected circuit.

In addition to the above features which are applicable to electrical apparatus generally, I have shown how an improved electro-responsive device according to the objects of my invention may be embodied into a removable unitary structure which is readily interchangeable with other devices of a similar character. I have also disclosed certain particular detailed structural arrangements which permit the controlling of 30 the time delay in the operation of electro-responsive devices, and various other preferred arrangements which are of value in carrying out the objects of my invention.

While in accordance with the patent statutes 35 I have disclosed the foregoing details of a practical embodiment of my invention, it is to be understood that many of these details are merely illustrative, and that variations in their precise form will be both necessary and desirable in 40 certain applications. I desire, therefore, that the language of the accompanying claims shall be limited only by what is explicitly stated therein and by the prior art.

I claim as my invention:

45 1. In electrical apparatus, an electro-responsive device including a flat strip of bimetallic material, means for connecting at least a portion of said strip into an electrical circuit, a heater connected in current-responsive relationship with said flat strip, said heater comprising a means of conducting material having a substantially flat looped portion, and means for supporting said heater on said strip, said support means including means for positioning the 50 looped portion of said heater in a plane that is substantially parallel to the plane of said strip and is spaced a substantial distance therefrom.

55 2. In electrical apparatus, an electro-responsive device including a flat strip of bimetallic material having a length several times its width, means for connecting at least a portion of said strip into an electrical circuit, a heater connected in current-responsive relationship with said strip, said heater comprising a means 60 of conducting material having at least one substantially U-shaped loop therein, and means for supporting said heater on said strip, said support means including means for positioning the side portions of said U-shaped loop in a plane 65 which is disposed a substantial distance from the plane of said strip and which is substantially parallel therewith.

70 3. An electro-responsive device for use in electrical apparatus comprising a pair of flat strips 75 of bimetallic material, means whereby said strips

may be fixedly supported adjacent one end thereof, the other end of said strips being movable to effect the operation of said device, insulating means for mechanically interconnecting said movable ends, means for connecting at least a portion of each of said strips into an electric circuit, a single unitary heater for both of said strips, electrically connected in series therewith, said heater including a conducting means having a plurality of loops formed therein, and means for supporting said heater on said strips, said support means positioning at least one of said plurality of loops in a plane substantially parallel to the plane of each of said strips.

4. An electro-responsive device for use with 15 electrical apparatus comprising a pair of flat strips of bimetallic material, each of which has a length several times its width, means whereby said strips may be fixedly supported adjacent one end thereof, the other end of each of said strips 20 being movable in the same direction to effect the operation of said device, insulating means for mechanically interconnecting said movable ends, means for connecting at least a portion of each of said strips into an electric circuit, a single 25 unitary heater for both of said strips, electrically connected in series therewith, said heater including a conducting means having a plurality of loops formed therein, and means for mechanically and electrically connecting one end of said 30 heater to each of said strips adjacent the movable end thereof, in order that said heater shall be entirely supported upon said strips, said connecting means being so arranged that said loops are positioned generally in a plane substantially 35 parallel to the plane of said strips.

5. In electrical apparatus, an electro-responsive device comprising a pair of flat strips of bimetallic material, each of said strips having a portion that is movable in the same direction 40 during the operation of said apparatus, insulating means for mechanically interconnecting said movable portions, means for connecting at least a portion of each of said strips into an electrical circuit, and a current-carrying heater connected 45 in electro-responsive relationship with said current-carrying portions and spaced some distance from said strips in order to decrease the rate of heat transfer therebetween.

6. In electrical apparatus, means for actuating 50 said apparatus, and an electro-responsive device for controlling the operation of said means, said device including a pair of flat strips of bimetallic material, insulating means for mechanically connecting said strips at one end thereof, means, supported on said connecting means, for operatively engaging said apparatus, means for connecting at least a portion of each of said strips into an electrical circuit, and a single current-carrying 55 heater for said strips, said heater being connected in series with said current-carrying portions, and being spaced some distance from said strips in order to decrease the rate of heat transfer therebetween.

7. In electrical apparatus, means for actuating 60 said apparatus, and an electro-responsive device for controlling the operation thereof, said device including a pair of flat strips of bimetallic material, insulating means for mechanically connecting said strips at one end thereof, means supported on said connecting means, for operatively engaging said means for actuating said apparatus, means for connecting at least a portion of each of said strips into an electrical circuit, a single unitary heater for both of said strips, and 65

70

75

75

- means for entirely supporting said heater on said strips of bimetallic material, said heater including conducting means for providing a conducting path between said portions of said strips 5 which are connected in an electrical circuit.
8. In electrical apparatus, means for actuating said apparatus, and an electro-responsive device for controlling the operation thereof, said device including a pair of flat strips of bimetallic material, means for supporting one end of each of said strips, the other end of each of said strips being movable, insulating means for mechanically connecting the movable ends of said strips, means, supported on said connecting means, for 10 cooperating with said means, for actuating said apparatus, means connecting at least a portion of each of said strips into an electrical circuit, a current-carrying heater connected in series with said current-carrying portions and spaced some 15 distance from said strips, and a sheet of an insulating material that is not affected by high temperature disposed in the space between said heater and said strips for decreasing the rate of heat transfer therebetween.
- 20 9. In an electro-responsive device a pair of flat strips of bimetallic material, means whereby each of said strips may be supported at one end thereof, the other end of each of said strips being movable during the operation of said device, insulating means for mechanically interconnecting said movable ends, means for connecting at least a portion of each of said strips into an electrical circuit, a current-carrying heater connected in series with said current-carrying portions 25 of said strips, and means for entirely supporting said heater on said strip, the support means for said strip including means for making possible the removal of said strips and said heater as a unit from said apparatus.
- 25 10. In a circuit interrupter, a base, separable contacts and an actuating means therefor fixedly mounted on said base, and a removable, current-carrying trip device operable upon the occurrence of predetermined conditions to effect the 30 operation of said actuating means, thereby causing said separable contacts to be moved to the open circuit position, said trip device including a pair of rigid terminal members which are adapted to engage said base member and upon which 35 the other elements of said trip device are supported, insulating means for mechanically interconnecting said terminal members to impart greater rigidity to said trip device, and a current-carrying, electro-responsive means electrically 40 connected across said terminals.
- 35 11. In a circuit interrupter, a base, separable contacts and an actuating means therefor fixedly mounted on said base, and a removable, current-carrying trip device operable upon the occurrence of predetermined conditions to effect the 45 operation of said actuating means, thereby causing said separable contacts to be moved to the open circuit position, said trip device including a pair of rigid terminal members which are adapted to engage said base member and upon which 50 the other elements of said trip device are supported, insulating means for mechanically interconnecting said terminal members to impart greater rigidity to said trip device, a pair of flat 55 strips of bimetallic material, means for connecting at least a portion of each of said strips into the electrical circuit through said current-carrying trip device, and a single heater means for both of said strips.

12. In a circuit interrupter, a base, separable contacts and an actuating means therefor fixedly mounted on said base, and a removable, current-carrying trip device operable upon the occurrence of predetermined conditions to effect the operation of said actuating means, thereby causing said separable contacts to be moved to the open circuit position, said trip device including a pair of rigid terminal members which are adapted to engage said base member and upon which the other elements of said trip device are supported, a pair of flat strips of bimetallic material, each of said strips having a portion which is movable in the same direction during the operation of said apparatus, means for mechanically interconnecting said movable portions, a single current-carrying heater means for said strips, and means for entirely supporting said heater on said strips.

13. In electrical apparatus, means for actuating said apparatus, and an electro-responsive device for controlling the operation of said actuating means, said device including a pair of flat strips of bimetallic material, each of said strips having a portion that is movable during the operation of said device, insulating means for mechanically interconnecting said movable portions, means for connecting at least a portion of each of said strips into an electrical circuit, and a current carrying heater connected in electro- 20 responsive relationship with said current carrying portions and being spaced some distance from said strips of bimetallic material, the electrical resistance and the thermal characteristics of said bimetallic members being such that the operation of said electro-responsive device is effected when a current of predetermined magnitude flows through said device for a predetermined time, and the electrical resistance of said heater and the spacing between said heater and 25 said members of bimetallic material being such that the operation of said electro-responsive device is also effected when a current of different predetermined magnitude flows therethrough for a different predetermined period of time.

14. In electrical apparatus, means for actuating said apparatus, and an electro-responsive device for controlling the operation of said means, said device including a pair of flat strips of bimetallic material, each of said strips having a portion that is movable in the same direction during the operation of said device, insulating means for mechanically interconnecting said movable portions, means for connecting at least a portion of each of said strips into an electrical circuit, and a current carrying heater connected in the electro-responsive relationship with said current carrying portions and being spaced some distance from said strips in order to decrease the rate of heat transfer therebetween, the electrical 50 resistance and the thermal characteristics of said bimetallic members being such that the operation of said electro-responsive device is effected when a current of predetermined magnitude flows therethrough for a predetermined time, and the electrical resistance of said heater and the spacing between said heater and said members of bimetallic material being such that the operation of said electro-responsive device is also effected when a current of considerably less 55 magnitude than said predetermined current flows therethrough for a considerably greater period of time than said predetermined time.

JOHN H. SHULER.
